UNITED STATES PATENT OFFICE.

DAVID FRIEDMAN AND SIMON EHRENFIELD, OF NEW YORK, N. Y.

DESIGN FOR A DISPLAY BOX OR SIMILAR ARTICLE.

Application filed October 21, 1927. Serial No. 23,839. Term of patent 7 years.

To all whom it may concern:

Be it known that we, DAVID FRIEDMAN and SIMON EHRENFIELD, both citizens of the United States, residing at New York, in the county of New York and State of New York, have invented a new, original, and ornamental Design for a Display Box or Similar Article, reference being had to the accompanying drawing.

The figure is a perspective view of a display box or similar article showing our new design.

We claim:

The ornamental design for a display box or similar article as shown.

In testimony whereof we affix our signatures.

DAVID FRIEDMAN.
SIMON EHRENFIELD.
